UNITED STATES PATENT OFFICE

2,119,784

LIQUID STERILIZING DEVICE

Edward A. Johnston, Chicago, Ill., assignor to International Harvester Company, a corporation of New Jersey

Application July 16, 1935, Serial No. 31,723
Renewed November 27, 1937

7 Claims. (Cl. 99—248)

This invention relates to an apparatus for subjecting liquids to the action of radiant energy. More specifically, it relates to an apparatus particularly designed for subjecting a liquid in a thin film to radiant energy generated by a tubular lamp or other similar sources.

In apparatus for sterilizing and otherwise treating milk with ultra-violet radiations it is very important in order to effect satisfactory results that the milk be formed as a very thin uniform film, preferably of a thickness less than one-tenth of a millimeter. In order to handle a sufficient volume of milk to effect treatment at a desired rate, it is also necessary to provide a large surface area on which the milk film is formed. Another important requirement is to provide an apparatus in which an atmosphere may be maintained which is transparent to the radiations which must reach the milk to effect the desired result. The atmosphere should also be inert to the action of the radiations and to producing any disagreeable odor in the milk.

The principal object of the present invention is to construct a machine for producing a thin uniform layer of liquid and maintaining the film for a time sufficient to subject it to radiant energy for a desired length of time.

Another object is to produce such a machine in which the time of exposure is controllable whereby an exposure may be obtained sufficient to produce the desired result and whereby overexposure with detrimental results may be avoided.

Another object is to provide a machine of the class described in which means are provided for supplying a thin film of regulated thickness to a cylinder rotating at a predetermined variable speed and in which means are provided for removing the film from the cylinder.

Another object is to provide a film forming and exposing means particularly adapted for use with a source of radiant energy in the form of a long tube, similar to the mercury vapor tubes in common use.

Another object is to provide a liquid film treating device in which the energy generating lamp is cooled to produce the most satisfactory results in a region in which the rays are not effective in performing a useful function.

A more specific object is to construct and build a machine so designed as to be readily taken apart for cleaning and servicing.

The above objects and others which will be apparent from the detailed description to follow are obtained in a machine such as is illustrated in the drawings in which:

Figure 1 is a side elevation of a complete machine with a portion of the driving end of the film forming cylinder broken away in section to better show its construction.

Figure 2 is a substantially horizontal section of the discharge end of the cylinder showing particularly the closure for that end of the cylinder through which an inert gas is fed into the cylinder.

Figure 3 is an end elevation of the machine shown in Figure 1 at the inlet end of the cylinder.

Figure 4 is an end elevation of the machine shown in Figure 1 at the outlet end of the cylinder.

Figure 5 is an enlarged end view of the outlet end of the cylinder showing the tube in section and the film forming and the liquid collecting means in end elevation.

As illustrated the machine is mounted on a supporting structure carried by a base 10. Arched supporting brackets 12 and 13 are secured by side bars 14 to form a rigid frame. An arched bracket 15 secured to the bracket 13 forms a support for a liquid tank 16 which is similar in construction to the milk bowls used on cream separators.

A plate 17, somewhat tri-angular in shape is secured to the bracket 12. Said plate is provided with a large central opening 18 through which a cylinder 19 extends. Said cylinder is mounted concentrically in the opening without touching the wall thereof by three rollers 20 pivotally mounted on bearing pins 21 suitably secured to the plate 17. Said plate and the rollers 20 associated therewith form a rotatable support for the lower end of the cylinder 19.

At its upper end the cylinder 19 is supported for rotation on three rollers 22. The upper roller is mounted on a bearing pin 23 secured to the upper portion of the arched bracket 13. The two lower rollers are supported on bearing pins carried by brackets 24 secured to the upper side portions of the bracket 13. The rollers 22 at the upper end do not contact directly with the cylinder 19 but run in an annular channel 25 formed in a flanged pulley 26. Said recess provides means for holding the cylinder against axial movement. The pulley 26 is secured to an outward and radially extending flange 27 rigidly secured to the upper end of the cylinder 19. Said pulley is secured by means of pins 28 threaded into the pulley and extended into openings in the flange. Cotter pins are utilized for maintaining the flange 27 against the pulley whereby the

cylinder may be readily removed by removing the cotter pins.

The pulley 26 is driven by a belt 28 which connects with a pulley 30 on a motor 31. Any suitable means may be provided for rotating the cylinder at the desired rate of speed. For example a variable speed electric motor may be utilized. It is important to provide a means for controlling the speed of rotation of the cylinder 19 as the speed determines the time of exposure which is an important feature in the treatment with radiant energy.

The cylinder 19 is of a uniform internal diameter, very finely finished and it is mounted and balanced so as to be driven with a minimum of vibration. For supplying milk to the cylinder an outlet from the tank 16 controlled by a valve 32 delivers milk through a flexible hose 33 to a delivery conduit 34 which terminates within the upper end of the cylinder 19 adjacent the bottom portion thereof. Milk delivered from the tank 16 through the conduit 34 flows down the inclined cylinder 19. The angle of inclination which is fixed by the cylinder mounting is determined by the viscosity of the liquid and the rate at which it is being removed from the cylinder by the film picked up by adhesion with the cylinder wall. The rate of delivery to the cylinder and the angle of inclination are factors which must be determined to meet the requirements desired.

Within the cylinder 19 a member 35 of a substantial width extends from end to end and beyond each end of the cylinder. Said member is provided with an upward extension 36 in the form of a flange at the side of the cylinder which moves in a downward direction during rotation, the direction of rotation being indicated by an arrow in Figure 5. A vertical upstanding supporting member 37 is rigidly secured to the member 35 spaced from the extension 36. Said member forms a point of attachment for a scraper element 38 which extends substantially parallel to the flange extension 36 and resiliently engages the inner wall of the cylinder. Said scraper element is formed of a material sufficiently thin and resilient to obtain substantially complete removal of a thin milk film from the wall of the cylinder. The flange 36, the member 37 and the scraper element 38 form an inclined trough down which the milk, removed as a film, flows to the lower end where it may be received in any suitable receptacle.

Referring to Figure 5, a film thickness regulating member 39 is secured to the member 35 extending therefrom adjacent the wall of the cylinder 19 at the side which is moving in an upward direction during rotation. Milk adheres to the wall of the cylinder and is carried upwardly. The normal thickness of the milk, assuming the cylinder to be wetted by the milk, would be determined by the cohesion of the milk particles. The film produced would, however, be too thick for irradiation purposes. It is for this reason that the regulating member 39 is employed. As illustrated, it is of a resilient nature being held in position by adjustable securing bolts 40. By adjusting these bolts the thickness of the milk film may be regulated.

At its lower end the member 35 and the structure carried thereby is supported on an end wall 41, as best shown in Figure 4. Said wall is provided with overhanging lugs which hold the member 35 against lateral movement while permitting endwise movement whereby it may be re-

moved from the cylinder. The wall 41 forms the end wall of a rectangular tank 42 extending the entire length of the cylinder and of a width substantially greater than the cylinder. The bottom of the tank slopes toward the end opposite the end wall 41, a drain cock 43 being provided for draining the tank. Said tank is provided largely for the purposes of receiving excess liquid delivered to the cylinder 19 which is not taken up as a film and which drains from the lower end of the cylinder. The liquid draining to the tank 41 is removed and passed through the machine a second time.

At its upper end the member 35 and the structure associated therewith are carried on a plate 44 which is rigidly secured to the member 35. Said plate is secured by removable bolts 45 to a member 46 which extends transversely across the arched bracket 18 being rigidly secured to said bracket. The conduit 34 previously referred to for delivering milk to the cylinder extends through an opening in the plate 44 and is brazed or otherwise secured thereto whereby it is removable with said plate and with the member 35 as a complete assembly.

The source of radiant energy, as illustrated, is a low vapor pressure glow discharge lamp. Said lamp is provided at each end with liquid mercury electrodes 47 cooled by water jackets 48. Cool water may be introduced at one end through a connection 49 into one jacket and circulated therefrom through a cooling jacket 50 extending the entire length of the central tubular portion 51 of the lamp.

It will be noted in Figure 5 that the water jacket 50 around the lamp extends an angular distance no greater than the distance occupied by the film forming and removing means. Radiations from the lamp over this area would be of no value as there is no film to be treated. This is an important feature of lamp construction in connection with a machine of this design. By utilizing either an integral cooling jacket or a jacket closely fitted against the lamp satisfactory cooling may be obtained by utilizing an area which in any event would be ineffective to produce a useful function. The importance of this feature is better appreciated when it is understood that ultra-violet radiations which are particularly effective for sterilizing and activating milk will not pass through ordinary tap water to any extent and will not pass through any substance or deposited impurity which might result from the use of cooling water. The exact nature of a very effective type of lamp, the precautions necessary to obtain satisfactory results are set forth in detail in the copending application previously referred to.

Water supplied through the inlet 49 after passing through the electrode cooling chambers and the water jacket 50 may be removed through an outlet 52.

The lamp tube 51 is supported at its upper end by an inverted U-shaped bracket 53. Said bracket is secured by a clamp around the tube 51. The lower ends of the bracket are removably secured to the member 46 by the removable bolts 45 previously described. The lower end of the lamp tube 51 is supported by a clamp 54 which is secured to the member 37 previously described.

In order to provide a closure for the lower end of the cylinder 19 a housing 55 is provided. As best shown in Figures 1 and 2 the housing includes a plate member 56 which fits against the end of the cylinder 19 in a substantially gas tight

manner. Said plate at its bottom side follows the scraper element 38, the upstanding member 37, the member 35 and the film forming member 39 being fitted in a substantially gas tight manner against these elements except for a cut-away portion 56' which forms an outlet for the milk whereby the upper portion of the cylinder above the member 35 may be substantially enclosed. A large central opening 57 is formed in the member 56 through which the lamp tube 51 extends. An extension housing 58 extending outwardly beyond the end of the cylinder is secured in a gas tight manner to the member 56 and around the tube 51. Said housing extends as shown in Figure 2 and in Figure 4 vertically and upwardly from one side of the member 37. Supporting bracket 59, as shown in Figure 4 is secured to the arched member 12 on top of the plate 17 and to the vertical wall portion 60 of the housing 58. A second bracket 61 is secured in a similar manner to the arched bracket 12 and to a cylindrical wall portion of the housing 58. An inert gas, such as carbon dioxide which does not absorb the radiant energy utilized is supplied to the housing 58 and therefrom through the opening 57 to the cylinder 19. Carbon dioxide is particularly suitable as it is heavier than air and maintains an atmosphere in the cylinder suitable for operation without closing the upper end of the cylinder.

30 The operation of the machine as described has been explained in connection with the description part by part. A machine of this type has been successfully operated with a milk treating capacity of 30 to 40 gallons per hour. The film thickness is accurate and can be maintained with the desired limits. The time of exposure is uniform and can be calculated and regulated as desired. The machine may be readily taken apart due to its construction as described for cleaning and re-40 placing the lamp and for cleaning the cylinder and the film forming and removing means.

45 The machine has been described as a milk treating device as this machine was developed primarily for that purpose. It is, however, evident that the machine may be used for whatever purpose desired when a thin liquid film is to be treated to a source of radiant energy available in a form such as a tubular lamp. Applicant therefore claims as his invention all modifications and all 50 the uses falling within the scope of the appended claims. In this description the lamp has only been briefly described. There are at present lamps available for irradiating milk and other fluids which could be used in the apparatus des-55 closed. The apparatus is intended for use with any type of radiant energy producing means which can be used successfully for accomplishing desired results by the treatment of a thin liquid film. All such lamps and their use applicant 60 contemplates as a part of his invention when utilized in his improved apparatus.

65 What is claimed is:

1. In a device for irradiating liquids the combination of a supporting structure, a cylinder rotatably mounted in a downwardly inclined position on said structure, means for rotating said cylinder whereby the liquid flows down the bottom of the cylinder and is picked up as a film by the cylinder at the side which is moving upwardly, 70 means for delivering liquid to be treated to the upper end of said cylinder, means within the cylinder extending axially thereof spaced with respect to the wall for controlling the thickness of the milk film adhering to the wall of the cylinder, 75 said means being positioned near the bottom of

the cylinder at the side moving in an upward direction, means in the cylinder near the bottom at the side moving downwardly for removing the film therefrom, and means for generating ultra-violet radiations extending axially of the 5 cylinder centrally thereof.

2. A device for irradiating liquids comprising a supporting structure, a cylinder rotatably mounted in a downwardly inclined position on said structure, means for rotating said cylinder, 10 means for delivering liquid to be treated to the upper end of said cylinder, means within the cylinder extending axially thereof spaced with respect to the wall for controlling the thickness of the film adhering to the wall of the cylinder, 15 said means being positioned near the bottom of the cylinder at the side moving in an upward direction, means in the cylinder near the bottom at the side moving downwardly for removing the film therefrom, means for generating ultra-violet 20 radiations extending axially of the cylinder centrally thereof, and means for maintaining an atmosphere in the cylinder substantially transparent to said radiations.

3. A device for irradiating liquids comprising 25 a supporting structure, a cylinder rotatably mounted in a downwardly inclined position on said frame structure, means for rotating said cylinder, means for delivering liquid to be treated to the upper end of said cylinder, means within 30 the cylinder extending axially thereof adjustably spaced with respect to the wall for controlling the thickness of the milk film adhering to the wall of the cylinder said means being positioned adjacent the bottom of the cylinder at the side 35 moving in an upward direction, a scraper element mounted in the cylinder axially thereof and positioned at the side of the cylinder moving downwardly for removing the film therefrom, a trough positioned to receive the liquid removed by said element and to deliver it from the cylinder, a container positioned below the lower end of the cylinder for receiving the liquid in excess of that removed as a film, and a means for generating ultra-violet radiations extending axially of the 40 cylinder centrally thereof. 45

4. A machine for treating milk comprising a frame structure, a cylinder rotatably mounted in a downwardly inclined position on said frame structure, means for rotating said cylinder, means 50 for delivering milk to be treated to the upper end of said cylinder, means within the cylinder extending axially thereof spaced with respect to the wall for controlling the thickness of the milk film adhering to the wall of the cylinder, said means being positioned near the bottom of the cylinder at the side moving in an upward direction, means in the cylinder near the bottom at the side moving downwardly for removing the film therefrom, and means for generating ultra-violet radiations 55 extending axially of the cylinder centrally there-60 of.

5. A machine for treating milk comprising a frame structure, a cylinder rotatably mounted in a downwardly inclined position on said frame 65 structure, means for rotating said cylinder, means for delivering milk to be treated to the upper end of said cylinder, means within the cylinder extending axially thereof spaced with respect to the wall for controlling the thickness of the milk film 70 adhering to the wall of the cylinder, said means being positioned near the bottom of the cylinder at the side moving in an upward direction, means in the cylinder near the bottom at the side moving downwardly for removing the film there-75

- from, means for generating ultra-violet radiations extending axially of the cylinder centrally thereof, and means for maintaining an atmosphere in the cylinder substantially transparent to said radiations.
6. A machine for treating milk comprising a frame structure, a cylinder rotatably mounted in a downwardly inclined position on said frame structure, means for rotating said cylinder, means for delivering milk to be treated to the upper end of said cylinder, means within the cylinder extending axially thereof adjustably spaced with respect to the wall for controlling the thickness of the milk film adhering to the wall of the cylinder, said means being positioned near the bottom of the cylinder at the side moving in an upward direction, a scraper element mounted in the cylinder axially thereof and positioned at the side of the cylinder moving downwardly for removing the film therefrom, a trough positioned to receive the liquid removed by said element and to deliver it from the cylinder, a container positioned below the lower end of the cylinder for receiving the milk in excess of that removed as a film, an enclosure over the lower end of the cylinder, means for supplying an inert atmosphere to the cylinder and means for generating ultra-violet radiations extending axially of the cylinder centrally thereof.
- 10 for delivering milk to be treated to the upper end of said cylinder, means within the cylinder extending axially thereof adjustably spaced with respect to the wall for controlling the thickness of the milk film adhering to the wall of the cylinder, said means being positioned near the bottom of the cylinder at the side moving in an upward direction, a scraper element mounted in the cylinder axially thereof and positioned at the side of the cylinder moving downwardly for removing the film therefrom, a trough positioned to receive the liquid removed by said element and to deliver it from the cylinder, and means for generating ultra-violet radiations extending axially of the cylinder centrally thereof.
- 15 7. A machine for treating milk comprising a

frame structure, a cylinder rotatably mounted in a downwardly inclined position on said frame structure, means for rotating said cylinder, means for delivering milk to be treated to the upper end of said cylinder, means within the cylinder extending axially thereof adjustably spaced with respect to the wall for controlling the thickness of the milk film adhering to the wall of the cylinder, said means being positioned near the bottom of the cylinder at the side moving in an upward direction, a scraper element mounted in the cylinder axially thereof and positioned at the side of the cylinder moving downwardly for removing the film therefrom, a trough positioned to receive the liquid removed by said element and to deliver it from the cylinder, a container positioned below the lower end of the cylinder for receiving the milk in excess of that removed as a film, an enclosure over the lower end of the cylinder, means for supplying an inert atmosphere to the cylinder and means for generating ultra-violet radiations extending axially of the cylinder centrally thereof.

EDWARD A. JOHNSTON.
